UNITED STATES PATENT OFFICE.

HOWARD HOLFORTY, OF OMAHA, NEBRASKA.

DESIGN FOR A HAT.

41,258.

Specification for Design.

Patented Mar. 21, 1911.

Application filed October 20, 1909. Serial No. 523,731. Term of patent 7 years.

To all whom it may concern:

Be it known that I, HOWARD HOLFORTY, a citizen of the United States, residing at Omaha, in the county of Douglas and State of Nebraska, have invented a new, original, and ornamental Design for Hats, of which the following is a specification, reference being had to the accompanying drawing, forming a part thereof.

The figure is a side view of a hat, showing my new design.

I claim:

The ornamental design for a hat, as shown.

HOWARD HOLFORTY.

Witnesses:

HIRAM A. STURGES,
FREDERIC BACON.

Copies of this design may be obtained for five cents each, by addressing the "Commissioner of Patents, Washington, D. C."
